UNITED STATES PATENT OFFICE.

JOHN L. TANDY, OF KANSAS CITY, MISSOURI.

SPRING-MATTRESS.

1,073,877.

Specification of Letters Patent. Patented Sept. 23, 1913.

Application filed November 16, 1911. Serial No. 660,728.

To all whom it may concern:

Be it known that I, JOHN L. TANDY, a citizen of the United States, residing at Kansas City, in the county of Jackson and 5 State of Missouri, have invented certain new and useful Improvements in Spring-Mattresses, of which the following is a specification.

This invention relates to spring mattresses 10 and its main object is to produce a light, rigid and cheap frame of such construction that its weight will be imposed upon the side bars of the bed frame at such points as to hold said bars in proper relation to the head 15 and foot ends, if said bed frame is of that type in which the head and foot ends are provided with downwardly-tapering sockets and the side bars with downwardly-tapering lugs to be fitted down into said sockets.

20 A further object is to produce a spring mattress provided with simple, cheap and efficient trusses for trussing the fabric and for guarding against undue lateral spreading or lateral movement of the ordinary 25 mattress adapted to fit upon the fabric.

A still further object is to provide auxiliary side guards for preventing lateral movement or spreading of the said ordinary mattress, and movable vertically upon the 30 side bars of the mattress frame and connected to the fabric so as to move up and down therewith.

With these general objects in view and others as hereinafter appear, the invention 35 consists in certain novel and peculiar features of construction and organization as hereinafter described and claimed; and in order that it may be fully understood reference is to be had to the accompanying 40 drawing, in which—

Figure 1, is a fragmentary plan view of a mattress embodying my invention. Fig. 2, is a side view of a portion of the same. Fig. 3, is an end view on a reduced scale, of the 45 frame, the mattress fabric and other parts shown in Figs. 1 and 2, being omitted. Fig. 4, is a section on the line IV—IV of Fig. 2. Fig. 5, is a similar view of a slightly modified construction, with the mattress fabric 50 and springs omitted. Fig. 6, is a section on the line VI—VI of Fig. 2.

In said drawings, 1 are the end bars of a frame, said bars being preferably of angle iron, as shown.

55 2 indicates the side bars, preferably of

tubing, and having their ends bent upwardly at 3 and terminating in flattened extremities 4, underlying the end bars and riveted or otherwise rigidly secured thereto at 5. To secure said end and side bars in rigid relation to each other, inclined truss braces 6 are employed, the arch portions of said braces being secured to the central portions of the adjacent end bars. The ends of the truss braces underlie and project beyond 65 and are secured to the side bars 2, inward of the upturned ends 3. The truss braces are preferably of angle iron, as shown most clearly in Figs. 2, 4 and 5, and their horizontal arms are adapted to rest upon the side 70 rails of a bed, as hereinafter explained, and their depending arms are cut away to provide shoulders 7, for engagement with the inner edges of said side rails, the latter being indicated in dotted lines, at 8, in Fig. 3. 75 By this construction and arrangement of parts, it will be seen that the mattress frame rests upon the side rails of the bed and tends to hold said rails in engagement with the head and foot ends, not shown, where such 80 ends are provided with sockets and the side rails with lugs to engage such sockets. In this connection it will be noted that the upturned ends of the side bars and the outwardly projecting ends of the truss braces 85 constitute "corner risers" and obviate the necessity of using the customary heavy cast-iron "corner risers" common in mattress frame construction.

9 is a wire fabric or mattress connected at 90 its ends by the usual helicals 10, to end bars 1, it being noted that the truss braces 6 guard against inward bending or bowing of the end bars under the pull imposed thereon by said fabric. To prevent the truss 95 braces from yielding or springing and thereby imposing endwise pressure on the side rails 8, tending to spring or bow the same outwardly, cross braces 11 may be employed, the same bridging the spaces between and 100 secured to the undersides of the extremities of the truss braces, the rivets 12 or equivalent fastening devices by which the truss braces are secured to the side bars, being utilized to also secure the ends of the cross 105 braces 11 to the truss braces.

For the purpose of trussing the wire fabric 9, I provide four trusses constructed as follows:—13 are standards arranged at 110 opposite sides of the fabric near its ends,

the lower portions of the standards underlying the fabric as shown in Figs. 1 and 4. In the preferred construction the standards 13 are split at their lower ends and bent to 5 form open spring sleeves 14, to fit around the side bars, and short legs 15, to rest upon the ends of the truss braces at the outer sides of bars 2, the lower ends of the legs being recessed to form tongues 16 to bear 10 against the inner sides of the ends of the truss braces as shown clearly in Figs. 2 and 4. By this arrangement the standards 13 are capable of being swung inwardly upon the fabric 9, and secured to the same in any 15 suitable manner for convenience of shipment, the helicals 10 yielding sufficiently for this purpose. The sleeves 14 constitute the pivotal points in such movements of the standards. The engagement of the legs 15 20 with the truss braces prevent the standards 13 from swinging outward when in operative position.

In the modified construction shown by Fig. 5, the cross braces terminate in upwardly projecting arms which constitute the standards 13. At their upper ends the said standards 13 are linked to the sides of the fabric at different points by a plurality of elastic connections 17, equipped by preference with helicals 18, to accommodate a limited downward movement of the fabric, and the strain imposed by the fabric through said connections 17 on the standards 13 is resisted by tie rods or wire connections 19 30 between the upper ends of said standards and the adjacent end bars of the frame, as shown clearly in Figs. 1 and 2.

In Fig. 5, a modified form of the fabric brackets is shown, the standards in said figure, being shown as upward extensions of the braces 11, and in this construction the upper ends of said extensions or standards are preferably connected by tie rods 20, to the end bars 1, the tie rods 20 extending 45 downwardly and inwardly to prevent outward bending movement of the standards.

The standards 13 and connections 17 and 18, tend to prevent lateral movement or spreading of the ordinary mattress, not 50 shown, adapted to rest upon the wire fabric mattress, and to coöperate in thus properly retaining said ordinary mattress on the fabric, I provide one or more side guards. Each of these guards, consists of a piece of 55 wire bent to U-form and then both arms of the U are bent so that the guard in side view shall be of step form, consisting of the tread portion 21, riser 22, projecting upwardly from the outer end of the tread portion and 60 a riser 23 depending from the inner end of the step portion and extending slidingly through holes 24 in the side bars 2 and terminating in laterally projecting portions 25 to limit the upward movement of the guard. 65 The tread portions 21 of the guard are pref-

erably bent at 26, so that their inner portions may lie in substantially the plane of the fabric 9 and at the junction of the inner ends of the tread portions and the upper ends of the risers 23, the guard is formed 70 with eyes 27 receiving longitudinal strands or links of the said fabric, so that when the latter is depressed or springs upward, the guard will slide downward or upward respectively, it being noted that the outer riser 22 occupies substantially the same vertical 75 plane as the corresponding side edge of the fabric and projects upwardly therefrom for the purpose of preventing undue spreading movement of the ordinary mattress. 80

From the above description it will be apparent that I have produced a spring mattress embodying the features of advantage enumerated as desirable, and I wish it to be understood that I reserve the right to make 85 all changes properly falling within the spirit and scope of the appended claims.

I claim:

1. A spring mattress, comprising a rectangular frame, consisting of end bars and 90 side bars, truss braces connecting the side bars inward of the adjacent end bars and also connected at intermediate points to said adjacent end bars, a wire fabric connecting the end bars and overlying the truss 95 braces, fabric trusses at opposite sides of the fabric near each end thereof and consisting of standards projecting upwardly beyond the fabric, tie rods extending from said standards to the adjacent end bars of 100 the frame, and elastic connections extending from said standards in the opposite direction and attached at their opposite ends to fabric.

2. A spring mattress, comprising a rectangular frame, consisting of end bars and 105 side bars, truss braces connecting the side bars inward of the adjacent end bars and also connected at intermediate points to the said adjacent end bars, cross braces between the side bars and secured in fixed relation to the same and the ends of the truss braces, a wire fabric connecting the end bars and overlying the truss braces, fabric trusses at opposite sides of the fabric near each end 115 thereof and consisting of standards projecting upwardly beyond the fabric, tie rods extending from said standards to the adjacent end bars of the frame, and elastic connections extending from said standards in 120 the opposite direction and attached at their opposite ends to the fabric.

3. In a spring mattress, a rectangular frame, consisting of end bars and side bars, the latter having upturned ends, secured at 125 their extremities to the end bars, and angle iron truss braces adapted to rest at their extremities upon the side rails of a bed frame and provided near such ends with outwardly-disposed shoulders to bear 130

against the inner sides of said bed rails, the truss braces between such extremities lying in inclined planes and being secured midway their length to the under surfaces of 5 the adjacent end bars of the rectangular frame.

4. A spring mattress comprising a rectangular frame, and a wire fabric covering and attached to the ends of the frame, and 10 truss braces at opposite sides of said fabric, each comprising a standard projecting from the said frame, a tie rod connecting the standard with the adjacent end of said frame, and an elastic connection extending 15 from said standard and attached to the fabric.

5. The combination with a spring mattress, comprising a rectangular frame and a wire fabric covering and attached to the 20 said frame, and side guards attached to said wire fabric at opposite sides of the same and connected to slide vertically upon the side bars of the said rectangular frame and provided in substantially the plane of the outer

side margins of said fabric with upwardly 25 projecting portions.

6. The combination with a spring mattress, comprising a rectangular frame and a wire fabric covering and attached to said frame, and side guards of step form in side 30 view, consisting of a tread portion resting upon the fabric at the side margins thereof and attached to the fabric inward of said side margins, risers extending upwardly from the inner ends of said tread portions 35 and risers depending from the inner ends of said tread portions and extending slidably through the side bars of said frame and provided with bent ends underlying the said side bars and adapted to engage the same 40 and limit the upward movement of said guards.

In testimony whereof I affix my signature, in the presence of two witnesses.

JOHN L. TANDY.
